SPACER PRIMER CARTRIDGE FOR
AMMONIUM NITRATE

Dean Elliott Albon and John Frank Barco, Du Quoin, Ill., assignors to Airmite-Midwest Incorporated, Du Quoin, Ill., a corporation of Illinois

Application May 7, 1957, Serial No. 657,692

2 Claims. (Cl. 102—22)

The present invention relates to primer cartridges employed for the purpose of detonating ammonium nitrate and is concerned primarily with a spacer cartridge that is particularly designed for accurate centering in a cylindrical blast hole.

In the copending application of John Frank Barco and Dean Elliott Albon, Serial Number 642,215, filed February 25, 1957 and entitled Primer for Ammonium Nitrate and Method of Using Same, there is disclosed a procedure under which a vertical blast hole is loaded with an explosive charge comprising about 90% ammonium nitrate and 10% primer cartridge. The whole idea behind the method of this copending application is to so arrange the prilled or granulated ammonium nitrate with respect to the primer cartridge so that none of the ammonium nitrate is located further from the primer cartridge a distance ranging from four to six inches. With such an arrangement, the ammonium nitrate is overdriven and has a rate of detonation comparable to that of the primer cartridge, whether it be dynamite or any other material employed for this purpose.

From the foregoing it is apparent that if the method of said copending application is to be properly carried out and the ammonium nitrate detonated with this overdriving effect, the primer cartridge should be accurately centered in the blast hole.

With the foregoing conditions in mind, the present invention has in view as its foremost objective the provision of a primer cartridge of the character aforesaid which is provided with means for accurately centering the same in a vertical cylindrical blast hole.

As explained in said copending application, the primer cartridge is ordinarily cylindrical and in accordance with the now prevailing conditions in strip mining operations, has a diameter of about 3" and is formed in sectional units, each of which has a length ranging from 12 to 16". Another object of the present invention is to provide a sectional unit of a primer cartridge which is readily adapted to having a spacer attachment applied to either end thereof.

In carrying out the above noted ideas in a practical embodiment, the present invention provides a primer cartridge unit consisting essentially of a cylindrical cardboard casing that is closed at one end by a thin metallic head that is crimped thereto and at the other end by an inverted cup-shaped cap. Extending between the head and cap is a tubular core which accommodates a primacord which may be knotted at one end to anchor that end to the lowermost of a plurality of such units when assembled. The spacer attachment is secured to the cup-shaped cap.

Another highly important object of the invention is to provide in a primer cartridge unit of the character aforesaid, a spacer attachment which consists essentially of a central hub from which outstand a plurality of arms. The hub is received in and affixed to the cup-shaped cap and with the radially extending arms of the same length, the cartridge is centrally positioned in a blast hole.

Inasmuch as it is impractical, if not impossible, to form a blast hole having a uniform cylindrical wall free of irregularities it is evident that with the arms of the spacer unit accurately dimensioned to conform to the diameter

2

of the blast hole, considerable difficulty would be experienced in lowering the primer cartridge units into a blast hole when the irregularities are present. Thus, another highly important object of this invention is to provide in a primer cartridge sectional unit of the type indicated radial arms having flexible end portions. These end portions preferably take the form of coil springs which are fitted onto the ends of solid rods with the latter in turn being received in sockets in the cylindrical hub.

10 In using sectional units of the character aforesaid in the loading of a vertical blast hole with ammonium nitrate, it is deemed preferable to arrange the lowermost unit with the spacer attachment at the bottom of the hole. The next unit which is located immediately thereabove is arranged with the spacer attachment at the top, and this is true of all other primer cartridge units which are included in the charge.

Various other more detailed objects and advantages of the invention such as arise in connection with carrying 20 out the above noted ideas in a practical embodiment will in part become apparent and in part be hereinafter stated as the description of the invention proceeds.

The invention therefore comprises a primer cartridge intended for use with ammonium nitrate which consists 25 essentially of a plurality of sectional units each comprising a cylindrical casing with a head at one end, a cup-shaped cap at the other, a tubular core extending between the head and the cap, a hub member received in and anchored to the cup-shaped cap and a plurality of 30 radially extending arms outstanding from the hub member and having flexible end portions.

For a full and more complete understanding of the invention reference may be had to the following description and accompanying drawings wherein:

35 Figure 1 is a side view with parts broken away and shown in section of a primer cartridge sectional unit designed in accordance with the precepts of this invention;

Figure 2 is a top plan view of the spacer attachment 40 per se;

Figure 3 is a detailed diametric vertical section through one end of the unit taken on an enlarged scale;

Figure 4 is a detail of a portion of one of the radial arms showing the flexible part in section;

45 Figure 5 is a perspective depicting the various elements of one of the units in exploded relation; and

Figure 6 is a vertical section of a blast hole showing the latter as loaded with ammonium nitrate using a primer cartridge made up of several sectional units of this 50 invention.

Referring now to the drawings, one unit of a sectional primer cartridge is shown as including a cylindrical casing 10. This casing is preferably of cardboard and when the cartridge is designed for use with blast holes having 55 a diameter in the nature of 10" which is common practice in strip mining, the casing 10 will be of a diameter of about 3". Its length may range from 12 to 16".

At one end the casing 10 has crimped thereto a head or bottom 11 which may be of thin metal such as aluminum, and it is formed on its periphery with an annular groove 12 which receives one end of the casing 10 and is crimped thereover. This head or bottom 11 is formed with a central aperture 13 that is defined by an inwardly extending flange 14.

60 The other end of the casing 10 is closed by a cup-shaped cap 15 having a peripheral flange 16 that is received in the bore of the casing 10 with a snug-fit. The cup-shaped cap 15 is arranged so that it opens outwardly to present a recess defined by the flange 16.

65 A spacer attachment is referred to in its entirety by the reference character A. The attachment A comprises a central hub made up of two wooden blocks 17 and 18

ch may be secured together in any preferred manner 5 as by the nails shown at 19. The block 17 is dimensioned so that it is snugly and accurately received in the cup-shaped cap 15. The block 18 is somewhat larger in diameter and its peripheral edge extends slightly beyond the casing 10. These blocks 17 and 18 are formed in a truncated conical opening 20 with the larger end 10 opening being disposed inwardly.

he block 18 has a cylindrical surface 21 that is formed 15 in a plurality of equi-angularly spaced sockets 22. In form of the invention illustrated in the drawings, four 20 these sockets 22 are formed in the block 18 but this number could obviously be varied without departing from spirit of the invention. Fitted in each socket 22 with 25 a pressed fit is a rod 23 which preferably is of wood and which extends outwardly from the block 18. Fitted over end of each rod 23 is a flexible coil spring 24. Thus, 30 a arm which extends radially outwardly from the hub 18 is made up of a rod 23 and a flexible section 24. Obviously, these arms should all be of substantially the 35 same length.

he cup-shaped cap 15 is formed with a central aperture 25 that is defined by an outwardly extending flange 26. 40 The aperture 25 is in alignment with the aperture 13 in head or bottom 11. A tubular core 27 is fitted in the 45 apertures 13 and 25 and is preferably received within the 50 tubes 14 and 26 with a pressed fit. At one end the 55 core 27 projects outwardly into the opening 20 formed in blocks 17 and 18. This tubular core 27 together with 60 opening 20 accommodates a primacord that is shown 65 8.

Assembling the spacer attachment A on the cap 15 70 block 17 is first fitted within the flange 16 in the manner shown in Figure 3, whereupon a pair of thumbs 29 are applied with the shank of each tack penetrating the casing 10, flange 16 and wooden block 17. It 75 may be noted that the cap 15 is also made of a thin metal and the flange 16 is thus readily adapted to being secured by the thumbtack.

Referring now more particularly to Figure 6, the manner of loading a vertical blast hole with ammonium nitrate and a primer cartridge made up of several units of invention will be described.

geological formation is represented at 30 and is 80 shown as being formed with a vertical blast hole 31. As pointed out above will ordinarily have a diameter of about 10". This blast hole 31 has a bottom at 32. 85 All of the units of this invention are first assembled so the spacer attachment A on one of the units will be first to enter the hole and a primacord 28 is passed through the tubular core 27. A knot 33 is formed in the 90 cord 28 for anchoring purposes. The other units are now 95 hung on the cord 28 so that the spacer attachment A is at the top of each of such units. The cartridge comprising these several units strung on the primacord 28 is then 100 inserted into the blast hole 31, which action is readily initiated by the flexible end sections 24 of the radially extending arms. When the attachment A reaches the bottom 105 of the hole, the various units making up the cartridge will be accurately centered. Prilled or granulated ammonium nitrate such as represented at 34 is now 110 packed into the hole 31 about the primer cartridge and to a height of about 4" above the uppermost unit of such a cartridge. Stemming, represented at 35, is then applied to the hole and confine the explosive charge. The primacord 28 extends upwardly through the stemming and is available to detonate the charge.

is evident that with each unit of the primer cartridge 115 accurately centered by the spacer attachment A, all of the packed ammonium nitrate will be so correlated with respect thereto that none of it will be located at a distance greater than 4" from the primer cartridge. Thus, when the latter is detonated the primer cartridge will be overdriven and attain the rate of detonation of the primer cartridge.

As shown in Figure 1, the casing 10 is filled with an appropriate detonating explosive such as a commercial grade of gelatin dynamite which is depicted at 36.

It has been found that with this arrangement a step-by-step overdriving effect may be obtained from the primacord to the primer cartridge and thence to the ammonium nitrate. Thus, with the ammonium nitrate having the lowest rate of detonation, the commercial dynamite 36 a higher rate and the primacord 28 a still higher speed of detonation, when the primacord 28 is detonated the dynamite 36 will be detonated and overdriven to achieve a speed of detonation greater than it would ordinarily exhibit. This increased rate of detonation of the dynamite is transmitted to the ammonium nitrate as the latter is overdriven. Thus, the ultimate effect is achieved of detonating the ammonium nitrate at a rate comparable to the speed of detonation of the primacord.

While a preferred specific embodiment of the invention is hereinbefore set forth it is to be clearly understood that the invention is not to be limited to the exact dimensions, constructions and materials illustrated and described because various modifications of these details may be provided in putting the invention into practice within the purview of the appended claims.

What is claimed is:

1. In a sectional primer cartridge, a unit comprising a cylindrical cardboard casing adapted to contain a detonating explosive, a metallic head crimped to one end of said casing and formed with a central opening, a cup-shaped metallic cap fitted in the other end of said casing and formed with a central opening, a tubular core received in said openings and extending between said head and cap, said core being adapted to accommodate a primacord, and a spacer attachment received in and secured to said cup-shaped cap, said attachment comprising a circular block snugly received in said cap, a second larger circular block secured to said first block and having a diameter greater than that of said casing, said blocks being formed with aligned openings in alignment with said tubular core, said second block having a peripheral surface formed with a plurality of angularly spaced sockets, and a radial arm received in each of said sockets.

2. In a sectional primer cartridge, a unit comprising a cylindrical cardboard casing adapted to contain a detonating explosive, a metallic head crimped to one end of said casing and formed with a central opening, a cup-shaped metallic cap fitted in the other end of said casing and formed with a central opening, a tubular core received in said openings and extending between said head and cap, said core being adapted to accommodate a primacord, and a spacer attachment received in and secured to said cup-shaped cap, said attachment comprising a circular block snugly received in said cap, a second larger circular block secured to said first block and having a diameter greater than that of said casing, said blocks being formed with aligned openings in alignment with said tubular core, said second block having a peripheral surface formed with a plurality of angularly spaced sockets, a rod received in each of said sockets, and a flexible coil spring carried at the free end of each of said rods, each rod and spring constituting a radial arm with all of said radial arms of substantially the same length.
